UNITED STATES PATENT OFFICE.

JOHN F. FORSYTHE, OF BLOOMINGTON, INDIANA.

RAIL-JOINT.

1,159,835.

Specification of Letters Patent.

Patented Nov. 9, 1915.

Application filed May 2, 1914. Serial No. 835,994.

To all whom it may concern:

Be it known that I, JOHN F. FORSYTHE, citizen of the United States, residing at Bloomington, in the county of Monroe and State of Indiana, have invented certain new and useful Improvements in Rail-Joints, of which the following is a specification.

My invention relates to improvements in rail joints and more particularly to such a device described and claimed in a patent issued to me May 13th, 1913, bearing #1,061,907.

As its primary object the invention contemplates an improved and simplified structure including a non-metallic filler or splice bar so arranged with respect to a specially devised fish plate as to form an adhesive bed therefor, this arrangement, as will appear hereinafter, greatly reducing the noise incident to the passage of rolling stock over rails as at present improperly joined.

The invention, as a further object aims to provide a rail joint wherein the fillers or splice bars are so arranged relatively to the rails and to the fish plates as to bear against the former throughout their entire length and to maintain the latter in slightly spaced relation to the rails, thereby increasing the bending resistance of the joint.

The above and additional objects are accomplished by such means as are illustrated in their preferred embodiment in the accompanying drawings, described in the following specification and then more particularly pointed out in the claim which is appended hereto and forms a part of this application.

In describing my invention in detail reference will be had to the accompanying drawings wherein like characters denote like or corresponding parts throughout the several views, and in which:

Figure 1 is a view of a rail joint in cross section; Fig. 2 is a section on the line 2—2 of Fig. 1; and, Fig. 3 is a detail perspective view of one of the filler bars.

Referring now to the drawings by numerals, 1 designates as an entirety an ordinary railway rail. The rails 1 to be joined are first placed with their adjacent terminals in engagement, fish or splice plates 2 being arranged, one upon each side of the meeting ends of the rail. The fish plates 2 are so formed as to bear against the under side of the tread portion of the rail as indicated at 3 and to rest upon the upper face of the

rail base as indicated at 4, the said plates extending over the respective longitudinal edges of the said rail base as indicated in Fig. 1, they being so shaped or formed as to extend in parallel spaced relation with the web portion of the rail. Bolts 5 extend transversely of the fish plates 2 and of the rails, said bolts serving as a means whereby the said plates are locked immovable with respect to the rails and as a means whereby the rails are properly joined and held or locked against longitudinal movement when so joined. The manner in which the bolts 5 are arranged having been fully described in my former patent above mentioned, further disclosure relative thereto would be unnecessary.

The inner or adjacent faces of the fish plates 2 are longitudinally grooved or concaved as indicated at 6, each groove or concavity receiving a non-metallic, (preferably wood) filler or splice bar 7, one longitudinal edge of which is shaped to conform to the configuration of the said groove or concavity 80 and the other face of which is substantially flat to bear, as illustrated in Fig. 1, against the web of the said rail. Openings 8 extend transversely of the filler 7 through which the bolts 5 extend. It will be noted that in my former patent the respective terminals of the fish plates 2 are cut away to expose the base flange of the rail. This feature having been found objectionable, the fish plates 2 of my present device are so constructed as to engage the base flange of the rail throughout the entire length of the former to strengthen the rail joint and to additionally brace the tread portion of the rail.

From the foregoing, taken in connection with the accompanying drawings it is apparent that the adjacent faces of the fish plates 2 are so arranged relatively to the web of the rails as to extend in spaced relation thereto, this arrangement, as pointed out above, reducing to the minimum the noise incident to the passing of rolling stock over the adjoining ends of the rails. It is also apparent that by so constructing the fish plates as to rest upon the base flange of the rail and to engage the under side of the tread portion thereof, the bending resistance of the rail joint will be increased; and that by constructing the splice bars or fillers 7 of material other than metal, the sound caused by the pounding of the wheels upon

the rails is deadened without in any way decreasing the efficiency of the joint.

In reduction to practice, I have found that the form of my invention, illustrated in the drawings and referred to in the above description, as the preferred embodiment, is the most efficient and practical; yet realizing that the conditions concurrent with the adoption of my device will necessarily vary, 10 I desire to emphasize the fact that various minor changes in details of construction, proportion and arrangement of parts may be resorted to, when required, without sacrificing any of the advantages of my invention, as defined in the appended claim.

Having thus fully described my invention, what I claim as new and desire to secure by Letters Patent, is:

In a rail joint, fish plates adjustable toward and from the web portion of the rail, 20 the top longitudinal edge of each fish plate being grounded to contact when in a finally

adjusted position the under side of the tread portion of the rail to afford a brace therefor, the inner face of each fish plate being longitudinally concaved throughout its length, a 25 filler of wood fitting each concavity, the filler being of a size to maintain the inner face of each fish plate in spaced relation to the said web portion of the rail and having a smooth inner face adapted for direct engagement with the said web portion of the rail and a convexed outer face shaped to fit the concavity aforesaid, the engagement between the filler and the rail leaving an unfilled space between the respective fish plates and the rail, and means maintaining the fish plates immovable relatively to the rail.

In testimony whereof I affix my signature in presence of two witnesses.

JOHN F. FORSYTHE.
